UNITED STATES PATENT OFFICE.

JOSEPH KEBOLA, OF NEW BRITAIN, CONNECTICUT.

RAZOR-STROPPING DEVICE.

1,080,981.

Specification of Letters Patent.

Patented Dec. 9, 1913.

Application filed November 27, 1912. Serial No. 733,791.

To all whom it may concern:

Be it known that I, JOSEPH KEBOLA, a citizen of Austria, residing at New Britain, in the county of Hartford and State of Connecticut, have invented certain new and useful Improvements in Razor-Stropping Devices, of which the following is a specification.

My invention relates to improvements in razor stropping devices, and the object of my improvement is simplicity and economy in construction and convenience and efficiency in use and it is particularly adapted for sharpening blades for safety razors.

In the accompanying drawing: Figure 1 is a plan view of my razor stropping device. Fig. 2 is a side elevation of the same. Fig. 3 is a sectional view on an enlarged scale on the line $z z$ of Fig. 1. Fig. 3^a is a similar fragmentary view, with certain parts moved from the position shown in Fig. 3. Fig. 4 is a view similar to Fig. 1 of certain parts shown therein. Fig. 5 is a similar view of the same, with certain parts moved from the 25 position shown in Fig. 4. Figs. 6 and 7 show different positions of some of the parts shown in Figs. 4 and 5. Fig. 8 is a sectional view on the line $y y$ of Fig. 1. Fig. 9 corresponds to Fig. 2 and is on the same scale, 30 with the carriage moved from the position shown in the said figure.

My razor stropping device comprises an elongated frame A on which is mounted a strap or strop proper B and also a carriage C provided with means for receiving and securing a blade D for a razor and having a handle 10 by which the said carriage C may be moved back and forth along the frame A and provided with mechanism to 35 be described for bringing the edge 11 of the blade into contact with the strop B as the said carriage is moved back and forth. The frame A comprises a pair of lateral members 12 formed of sheet metal strips on edge and 40 suitably spaced and held in position by cross-bars 13.

Notches 14 are provided in the upper edges of the lateral members or side strips 12 and near the ends thereof for removably 45 receiving the laterally disposed ends of end bars 15 to which are attached the ends of the strop B. At one of the ends of the side strips 12 shown as the front end there is provided a series of the such notches 14 so that a mating pair thereof may be selected for use according to the tension desired for

the said strop B. At the front end of the side strips 12 there is provided a pair of pivot holes 16 one in each strip for a tension handle E to be described.

60

The carriage C comprises a U shaped or channel piece of sheet material having the cross member 17 extending across below the side strips 12 and engaged with the lower edges thereof and the lateral arms 18 extending upwardly from the ends of the cross member 17 and engaged with the outer lateral faces of the side strips 12 and having the upper ends 19 extending upwardly above the upper edges of the said side strips and provided in the said upper ends with centrally disposed pivot holes 20 for the driving shaft 21 and with a pair of holes 22 one in front and one in rear of the said shaft pivot holes 20 in which are secured short pins 23 70 on which are mounted guide rolls 24. Ears 25 extend downwardly from the middle of the cross member 17 of the carriage C in which is pivotally mounted the upper end of the handle 10.

75

Near each end of the shaft 21 and adjacent the side strips 12 there is rigidly mounted a grooved driving wheel 26. At the middle of the shaft 21 there is rigidly mounted a backing plate 27 that is suitable to receive 80 and to support the blade D, and which is secured thereto by means of a sleeve or knuckle 28 surrounding the shaft 21. The backing plate 27 is essentially a hinge member, comprising the leaf 29 of plate-like 85 form suitable to serve as the support for the blade D and the knuckle 28 corresponds to the middle knuckle of a hinge, except that it is rigidly attached in a suitable manner to the shaft 21 that serves as the pintle for the 90 movable hinge member or clamping plate 30. The said movable hinge member 30 comprises a pair of end knuckles 31 pivotally mounted on the pintle or shaft 21 and positioned one on each side of the middle or 95 intermediate knuckle 28 and from which extends radially the leaf 32.

100

The leaves 29 and 32 when in closed position are spaced suitably to be an approximate fit for the blade D and they are actually spaced so that the free ends will engage with the blade and clamping means are provided for clamping the said leaves to the blade. As shown the clamping means comprise a pair of laterally disposed lugs 33 extending upwardly from the lateral ends of the bottom of one of the leaves, shown as 110

leaf 29 and overhanging the plate surface on the inner or blade side and spaced suitably therefrom to admit the thickness of the blade D, leaf 32, and wedge shaped 5 clamping ends 36 of the bar 34 which constitutes the clamping means proper. The bar 34 is pivotally mounted by its middle on the outer face of the leaf 32 by means of a pivotal pin 35 so that the same may be 10 swung around flush with the outer surface of the said leaf 32 and so that the ends 36 already mentioned may be entered between the free ends 37 of the lugs 33 and the surface of the leaf 32. The leaf 32 is provided 15 with notches 38 which clear the ends 36 of the lugs 33 as the leaf 32 is swung to and from the clamping position.

The cross bar 15 at the rear end of the strop B supports the said rear end of the 20 strop and also has secured thereto the rear ends of a pair of driving belts 39. The front ends of the belts 39 are secured to the cross-bar proper 40 of the tension device E, the ends of which are pivotally mounted in 25 the holes 16 in the side strips 12 as already mentioned. The tension device E comprises the cross bar portion 40 and a handle portion 41 extending radially therefrom at about the middle thereof. As shown the 30 tension device E is formed of a single piece of wire having the end portions in alignment and forming the cross-bar portion 40, the outwardly directed free ends being engaged with the holes 16, and the inner portion being formed into a loop forming the handle 41.

The cross-bar portion 40 constitutes a shaft on which are mounted, one on each side of the handle 41, the front ends of the 40 driving belts 39. By rotating the cross-bar 40, as by means of the handle 41, the end of the belt 39 secured thereto will roll up on itself or build up or will unroll so as to vary the tension of the belt 39 accordingly.

45 Intermediate the ends each of the belts 39 pass under the guide rolls 24 and over the upper periphery of the driving pulley 26 so that the belt is engaged with the greater part of the said upper periphery, or for 50 nearly 180 degrees of the pulley surface.

Movement of the carriage C longitudinally along the frame A by means of the handle 10 carries with it of course the driving pulleys 26, wherefore the relation of the 55 said driving pulleys 26 and the belt 39 will vary as the movement mentioned is effected. It will be noted that the effect of the engagement of the driving belts 39 with the pulleys 26 will be to tend to turn the shaft 60 21 so that the parts connected thereto are positioned on the upper side of the strop B in a direction that is the reverse of the particular longitudinal direction of movement of the carriage C. The result of this 65 condition will be that the blade clamping

device composed of the relatively fixed member or backing plate 27 and the movable member or clamping plate 30 will be swung so that the edge 11 of the blade D will be brought into contact with the surface of the strop B by a rotary movement of the shaft 21. As such contact of the blade and the strop limits further rotary movement of the shaft 21 and the blade clamping device, it is evident that the result of further continued longitudinal movement of the carriage C along the frame A is to drag the blade D along the strop B, and thereby effect the stropping of the blade D desired. A reversal of the movement of the carriage C operates to bring the opposite side or edge of the blade D into engagement with the strop B. Accordingly, by moving the carriage C back and forth as by means of the handle 10, the opposite sides of the edge 80 of the blade are brought successively into contact with the strop.

During the stropping operation described the rear end of the frame A may be supported on any convenient support by 90 means of the hooked end 42 and the front end may be supported by means of the handle 41 of the tension device E whereby the tension of the driving belts 39 will be under control during the normal conditions of operation at will, and may be changed at will.

The movement described for effecting the stropping of the razor blade as the carriage is moved back and forth consists of flopping the blade back and forth by a movement of more than 180 degrees as the direction of movement of the carriage is reversed, the movement in each case being determined by the contact of the blade edge with the strop, and the stropping desired is effected by a continuation of the particular longitudinal movement of the carriage. The flopping movement described is due to the engagement of the driving belts with the driving wheels or pulleys as is also the tension or pressure of the blade edge in its engagement with the strop. Accordingly, it is evident that a variation of the tension of the driving belts by a change in the angular position of the tension device will result in varying the degree of such tension or pressure as the blade edge is moved along the strop.

I claim as my invention:—

A razor stropping device comprising a frame having side bars, a carriage slidably mounted thereon and having a shaft, and a driving pulley and blade holding devices on the said shaft, and a strop mounted on the said frame, a belt engaged with the said pulley, one end thereof being fixed to one end of the said frame, and a combined frame support and tension device positioned at the other end of the said frame and comprising a shaft portion pivotally mounted be 120 125 130

tween the said side bars, and a handle portion extending radially from the said shaft portion, and the other end of the said belt being attached to the said shaft portion, whereby the said handle portion may be grasped by the hand and serve to support the corresponding end of the said frame and at the same time can be manipulated to vary the tension of the said belt.
